UNITED STATES PATENT OFFICE

ARTHUR P. ARMINGTON, OF WILLOUGHBY, OHIO, ASSIGNOR TO THE EUCLID ROAD MACHINERY COMPANY, OF EUCLID, OHIO, A CORPORATION OF OHIO

TREAD LINK

Application filed October 27, 1931. Serial No. 571,377.

This invention relates to endless tread linkages of truss-forming or beam-forming type, such as those employed in connection with pairs of idler wheels to form the so-called "track-laying" wheel substitutes.

It is in the stretches of the linkage between wheels, and particularly in the lower, ground-engaging stretch, that the beam-forming or truss characteristic is desired.

10 Hereinafter is considered specifically only the ground-engaging stretch, and unless otherwise stated, links are assumed as being therein.

15 The loading upon the ground-engaging stretch of the linkage, if the ground be soft, is somewhat distributed throughout the stretch between leading and following wheels. Repeatedly, however, even in soft earth the linkage is run over projections such as 20 boulders, in which event the loading on the stretch is characteristically that of a concentrated load traveling along a beam. And where the stretch has curvature and the linkage is moved over hard earth as a pavement, the loading is characteristically a concentrated one fixed at the center of the stretch.

25 It will be apparent that the maximum stresses in a stretch will be normally at the center of the stretch, as when the stretch has curvature, and occasionally will move along the stretch as when the linkage is run over a projection; and this is true both of the compression members in a stretch, the shoe portions and pins, and of the truss members of the links. The primary forces imposed upon the stretch are the downward forces of the two wheels at the ends of the linkage, and the upward force of the supporting surface, normally at the center of the stretch although under certain conditions, elsewhere along the stretch. Thus as a link moves relative to its stretch from one end to the other thereof, there is a reversal of the vertical forces imposed thereupon, and this reversal takes place at the instant the loading upon the link is the greatest, in other words, as the linkage progresses through the zone of maximum stress intermediate the ends of the stretch.

30 Of course the initial fit of the pins in the

lug of the links is not perfect, and since the linkage is operated unlubricated, in sand, mud, and generally under the most adverse conditions, wear is bound to develop more or less rapidly at the pins.

An object of my invention is to minimize this wear, by eliminating translatory motion of the links upon their pins when the latter are loaded.

35 Where the truss members are rigidly associated with the other parts of their links, and particularly where the abutting faces of the truss members are disposed in vertical planes, any lost motion at the hinge pins will allow an equal sliding motion between these 40 abutting faces as the described vertical forces are reversed in the stretch of linkage. And since this sliding occurs when the faces are bearing against each other with maximum pressure, wear upon the faces is tremendous. 45 Such wear is highly undesirable as it results in a loss of curvature of the ground-engaging stretch, ultimately allowing the stretch to sag upwardly between the wheels.

50 Another object of my invention is to eliminate this wear between abutting faces of the truss parts, by so arranging the parts that there will be no motion between these faces when they are in abutting relation.

55 Briefly, the objects of my invention are accomplished by the simple expedient of arranging the faces of the truss parts in sloping planes so related with the hinge pins that when a link is functioning in a stretch of linkage, the sum of the opposite resultant forces 60 in said faces due to their cooperative connection will be less than the friction therebetween, as the links progress through the zone of maximum stress in the stretch; and more directly with reference to the pins, the relation of parts is such that the forces exerted upon a pin do not materially change direction throughout the zone. In other words, the end portion of one link will act as a wedge 65 upon the near end portion of the next link, to maintain the position of the parts relative to the pin joining them; the wedging action will be initiated to seat the parts at the beginning of the stretch, and will continue and 70

prevail upon the pins substantially throughout the stretch.

The exact nature of this invention together with further objects and advantages thereof will be apparent from the following description taken in connection with the accompanying drawings, in which Figs. 1, 2 and 3 are plan view, and end and side elevations respectively of a link embodying my invention; Fig. 4 is a conventionalized showing of a linkage made up from improved links as shown in Figs. 1 to 3, parts being shown in section, and Fig. 5 is a showing similar to Fig. 3 but with parts broken away and with forces indicated as acting upon the link when the latter is in a stretch.

With reference now to the drawings and particularly Figs. 1 to 3 thereof, the shoe or tread portion 1 of the link is lowermost, having a bottom ground-engaging surface 2 and thereabove a pair of rail sections 3 for supporting wheels. The shoe portion has hinge-pin-receiving openings 4 at its ends, located in the usual projecting lugs 5, which latter are staggered so that a pair of links may be joined by a single hinge pin, and an endless linkage may thus be assembled from a plurality of links and an equal number of pins.

A pair of truss members 6 and 7 extend upwardly from the shoe portion of the link, and may be integral therewith and joined with each other as shown. The member 6 is a hook member and has a face 8, and the member 7 is an eye member and has a face 9. The member 7 is preferably above the shoe portion and the member 6 overhangs the latter as indicated to provide better clearance at the bights of the linkage. The eye member 7 is supported by the webbing indicated, forming a canopy within which the hook member 6 of an adjacent link may move about the pin connecting the links. The arch of the canopy may be strengthened by upstanding flanges 10, and various clearance openings such as at 11 are provided for extrusion of accumulated foreign matter and as at 12 for foundry convenience.

The faces 8 and 9 are flat and arranged in sloping planes. The plan of the face 8 is one which passes between the hinge-pin openings 4 on the opposite ends of the link, and preferably substantially equidistant therefrom. The plane of the face 9 is substantially parallel with that of the face 8. Exact parallelism would result in all of the openings 4 lying in the same plane in a stretch of the linkage, which is not desirable. Therefore, preferably the plane of the face 9 is slightly out of parallel, converging upwardly toward that of the face 8, so that the pitch spacing of the faces 8 and 9 is slightly less than that of the openings 4, and the stretch of linkage has a slight curvature.

With reference now to Fig. 4, a linkage of my improved links such as appear in Figs.

1-3 is shown. Here the links are shown as connected by greatly undersized hinge pins 14, and the forces imposed upon the stretch are the downward forces B and C at the ends and the intermediate upward force A. It will be seen that all of the pins 14 assume the same identical position relative to adjacent parts, throughout the stretch. There is, therefore, no motion either of the pins or thereabout in the stretch, and this is true although the vertical forces upon the links are reversed as the point of maximum stress, at A, is passed. Neither is there relative motion between the abutting faces of the hook and eye members 6 and 7. In fact it is because of the sloping planes of these faces, and their relationship with the hinge pins, that there is no motion; for throughout the stretch there is a wedging action of each link upon both its adjacent links tending to jam and maintain the pins in the relative positions shown. And the result is that the relationship of the links throughout the stretch is constant as indicated in the line 16.

This may be illustrated with reference now to Fig. 5, assuming the link shown to be one functioning in the stretch as in Fig. 4. At the left end of the link the force D is impressed upon the face 8 by the next following link acting as a bellcrank about the pin in the corresponding opening 4. Similarly, at the opposite or forward end, the force E is impressed upon the face 9 by the link next ahead. These forces, however, do not act perpendicularly to the faces 8 and 9, as has been characteristic of the prior art. Instead, they act perpendicularly to the planes of their hinge pins, as indicated by the dot-dash lines, Fig. 5, and thus obliquely to the faces 8 and 9. Consequently they have cam action upon the faces, to maintain the link in the relation indicated in Fig. 4.

The hook member 6, therefore, acts as a wedge to jam between the adjacent hinge pin 14 and the eye member 7 of the adjacent link, against which the hook member bears; and the force of this wedging action is sufficient that, as the link progresses through the zone of maximum stress, intermediate the ends of the stretch, the force A does not affect the position of the hinge pin, or, what is more important, the relative positions of the abutting faces.

What I claim is:

1. In a tread link of the class described and having a shoe portion with hinge means at its ends, and truss members extending upwardly, said truss members having faces adapted to abut corresponding faces of adjacent similar links connected by hinge pins in a stretch of linkage, to impart beam characteristics to the stretch, said faces being so inclined with reference to the location of said hinge means that while the linkage progresses through the zone of maximum

stress intermediate the ends of said stretch, said faces will cooperate with cam characteristic to maintain substantially constant the direction of resultant forces acting upon said hinge pins.

2. In a tread link of the class described and having a shoe portion with hinge means at its ends, and truss members extending upwardly, said truss members having faces adapted to abut corresponding faces of adjacent similar links in a stretch of linkage to impart beam characteristics to the stretch, said face of one of said truss members being arranged in a plane which passes between the hinge means on the opposite ends of said link, and said face of the other member being substantially parallel with said plane.

3. In a tread link of the class described and having a shoe portion with a hinge at each end, and truss members extending upwardly, said truss members having faces adapted to abut corresponding faces of adjacent similar links in a stretch of linkage, to impart beam characteristics to the stretch, said face of one of said truss members being arranged in a plane which passes substantially equidistant between the hinges on the opposite ends of said link, and said face of the other truss member being substantially parallel with said plane.

4. In a tread linkage of the class described, a pair of links having shoe parts, hinge means connecting said parts for relative coaxial motion, said links having truss-forming parts upstanding from said shoe parts when the latter are in ground-engaging position, said truss-forming parts having faces interengageable to limit said motion in one direction, said faces being arranged to define by interengagement, when said tread parts are in said position, a sloping generally transverse surface, from the mean plane of which said hinge means is substantially removed, whereby when forces are applied to said links to cause interengagement of said faces, as in a ground-engaging stretch of said linkage, said limiting engagement of said faces will have coincidental cam characteristic effective at said hinge means to maintain the direction of resultant forces acting thereupon substantially independent of vertical forces imposed in the functioning of said linkage through said stretch.

In testimony whereof I hereby affix my signature.

ARTHUR P. ARMINGTON.
